(57) **CLAIM**

The ornamental design for a curb style storm drain filter, as shown and described.

DESCRIPTION

FIG. 1 is a top perspective and exploded view of the curb style storm drain filter of the instant invention;

FIG. 2 is a top perspective and partially exploded view thereof;

FIG. 3 is a top view thereof;

FIG. 4 is a front view thereof;

FIG. 5 is a rear view thereof;

FIG. 6 is a right side view thereof; and,

FIG. 7 is a left view thereof.

The portions of drawings illustrated by broken lines are for illustrative purposes and form no part of the claimed design.
